UNITED STATES PATENT OFFICE.

HAROLD H. RAYNOR, OF NEW YORK, N. Y., ASSIGNOR TO LES PARFUMS DE ROSINE, INC., OF NEW YORK, N. Y., A CORPORATION OF DELAWARE.

DESIGN FOR A BOX OR SIMILAR CONTAINER FOR TOILET PREPARATIONS.

Application filed October 26, 1926. Serial No. 19,490. Term of patent 14 years.

To all whom it may concern:

Be it known that I, HAROLD H. RAYNOR, a citizen of the United States, residing in the city, county, and State of New York, have invented a new, original, and ornamental Design for a Box or Similar Container for Toilet Preparations, of which the following is a specification, reference being had to the accompanying drawing, forming a part thereof.

In this drawing:

Figures 4 and 5 are views in elevation of the container taken from still other viewpoints.

I claim:

The ornamental design for a box or similar container for toilet preparations, substantially as shown.

HAROLD H. RAYNOR.
